UNITED STATES PATENT OFFICE.

MAURICE BLUMENTHAL, OF BROOKLYN, NEW YORK, ASSIGNOR TO B. S. BARNARD AND COMPANY, OF NEW YORK, N. Y., A CORPORATION OF NEW YORK.

CONDUIT-JOINT WRAPPER.

1,238,383.

Specification of Letters Patent. Patented Aug. 28, 1917.

Application filed December 14, 1915. Serial No. 66,874.

To all whom it may concern:

Be it known that I, MAURICE BLUMENTHAL, a citizen of the United States, and resident of Brooklyn, in the county of Kings and State of New York, have invented certain new and useful Improvements in Conduit-Joint Wrappers, of which the following is a specification.

This invention relates to wrappers for the joints of conduits such as are used underground as ducts for electrical conductors and analogous purposes, and it has for its object to provide a simple and improved wrapper for this purpose which will maintain a perfect fit completely around the conduit, which will be permanently adhesive with relation thereto, which will be absolutely water and acid proof, and which will furthermore possess advantages in convenience of application, inexpensiveness, effectiveness, and general efficiency.

In the drawings—

Figure 1 is a plan view of a portion of the fabric base of the improved wrapper.

Fig. 2 is a plan view of the reverse side of the fabric base as shown in Fig. 1.

Fig. 3 is a plan view of a portion of the wrapper in its completed condition ready for use.

Fig. 4 is a plan view of the reverse side of the wrapper in completed condition as shown in Fig. 3.

Fig. 5 is a side view illustrating a conduit joint with the improved wrapper in position thereon and partly broken away to show the relative construction.

Fig. 6 is a transverse sectional view across a conduit at the joint portion and showing the improved wrapper in position thereon.

Corresponding parts in all the figures are denoted by the same reference characters.

Conduits of the construction to which my improved wrapper particularly relates are usually formed of vitrified clay, but it will be understood that the wrapper is adapted for effective service conditions with relation to conduits of any material and under various conditions of use.

Referring to the drawings, 1—1 designate

their end edges closely abutting and forming a joint, as at 2. My improved wrapper is constructed in suitable strips or lengths, which may be rolled and fed from a reel in commercial usage and cut into sections of the desired length to be wrapped around the conduit joints.

The improved wrapper comprises a fabric or textile base, 3, which in the preferred construction consists of a strong twine interwoven as warp and woof threads, as shown at 4, with an open mesh, as shown at 5, and having a facing at one surface, as shown at 6, covering the twine and closing the mesh. The facing is preferably constituted by a pulp applied to the textile fabric, but it may be of any other suitable character or material. While I have illustrated the preferred type of the fabric base of the wrapper, as above described, under some conditions of use the textile base may be employed without the facing 6, or the open-mesh fabric may be flattened in rolls to spread the threads and reduce or close up the open mesh, or the fabric may be closely woven or be of any suitable weave with or without the facing 6, as will be readily understood. It is of course essential that the fabric be of strong character adapted to the effective purpose in which the wrapper is employed, and be of sufficiently pliable nature to enable its convenient application to the conduit joint in the manner hereinafter set forth.

The fabric or textile base 3 carries throughout its body and over its surfaces a filler, shown at 7, which is water and acid proof and thoroughly impregnates the fabric, and which is permanently of a "tacky" or adhesive character whereby the entire surface and body mass of the wrapper has permanently the characteristics just stated.

The filler 7, which thoroughly impregnates the body of the wrapper and is carried by the fabric or textile base thereof, is constituted by a suitable compound which in its constituents affords the impervious and permanently adhesive or tacky characteristics above mentioned. The preferred filler element of the wrapper is constituted by ani-

100

mal or vegetable fats or oils combined with mineral waxes, such as ozocerite, mineral caoutchouc, gilsonite, or retinite, the compound having a melting point approximately as high as 375° F.

In practice, the filler is combined with the fabric or textile base by any suitable method. In the preferred method of constructing the improved wrapper, the fabric or textile base 3 is passed in a continuous strip through a bath constituted by the filler compound 7 in solution at the desired melting point, whereby the fabric base is thoroughly impregnated with and covered at all its surfaces by the filler compound. The impregnated strip, after subjection to the bath, may then be rolled or reeled in condition for commercial use, and under the characteristics of the filler compound has a permanently adhesive or tacky surface condition which will not be impaired by the exposures incident to the general handling and usage of the wrapper.

In Figs. 5 and 6 I have illustrated the method of applying my improved wrapper to a conduit joint. After the conduit sections 1-1 are abutted together at the joint 2, it is simply necessary to draw the wrapper strip, shown at 8, having the construction and characteristics according to my invention, around the conduit joint so that it completely covers and incloses the same, and in this application of drawing the wrapper around the joint the permanently adhesive or tacky characteristics thereof will cause the wrapper to positively and effectively adhere to the surface of the conduit at all points of contact therewith. The ends of the wrapper strip 8 are preferably overlapped a suitable distance, say, about 3 inches, and the overlapped portions are pressed together, thus effecting a tight and permanent adhesion between the overlapped ends of the strip and maintaining the drawn length of the wrapper in a snug and permanently adhesive fit completely around the conduit. The impervious and permanently adhesive characteristics of the wrapper thus produce an absolutely water and acid proof closure of the conduit joint, which is permanently maintained by the inherent character of the wrapper itself, and the cement surfacing which is usually placed over the joint wrappers of conduits therefore does not affect the water-proof conditions but the cement surfacing over the wrapper effectively co-acts with the characteristics thereof and is adapted to perfectly adhere to the wrapper, by reason of the rough texture of the fabric or textile body thereof, thus producing enhanced joint conditions in which there is no possibility of leakage of cement or water into the conduit joint.

The operation and advantages of my in-

vention and improvements will be readily understood by those skilled in the art to which they appertain. The improved wrapper is not only of simple and inexpensive construction and capable of convenient application, in contradistinction to the joint closures or wrappers which have heretofore generally been employed, but it provides an absolutely water-proof covering at all points of the conduit joint and maintains a permanent adhesion and close adherence to the conduit surface at all points throughout the area of the wrapper.

I do not desire to be understood as limiting myself to the detail features of construction as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. An improved conduit-joint wrapper constituted by a flexible strip comprising a fabric or textile base having interwoven warp and woof threads with an open mesh and a facing covering the threads and closing the mesh and a body compound impregnating the textile base and facing and covering the entire surface thereof and having a permanently water-proof and adhesive character.

2. A conduit-joint wrapper consisting of a flexible strip having a fabric or textile base carrying a body compound impregnating the textile base and covering the entire surface thereof and having permanently water-proof and adhesive character which is imparted to and inherently and permanently maintained by the wrapper.

3. A conduit-joint, consisting, in combination with the conduit sections, of a flexible strip drawn completely around the joint and constituted by a fabric or textile base carrying a body compound impregnating the textile base and filling the mesh and covering the entire surface thereof and of permanently water-proof and adhesive character, said wrapper strip having a permanent adhesion to the surface of the conduit sections at all points of contact therewith.

4. A conduit-joint, consisting, in combination with the conduit sections, of a flexible strip drawn completely around the joint and having its ends overlapped, said wrapper strip being constituted by a fabric or textile base carrying a body compound impregnating the textile base and filling the

mesh and covering the entire surface thereof and of permanently water-proof and adhesive character, whereby the body of the wrapper strip has a permanent adhesion to the surface of the conduit sections at all points of contact therewith and a permanent adhesion at the overlapped ends of the strip

to maintain the drawn length of wrapper in a snug and permanently adhesive fit completely around the conduit.

In testimony whereof I have signed the foregoing specification. ¹⁰

MAURICE BLUMENTHAL.
